UNITED STATES PATENT OFFICE

135,787

DESIGN FOR A WATERPROOF JACKET

John E. Hard, Cranston, R. I., assignor to Good-year Footwear Corporation, Providence, R. I., a corporation of Delaware

Application September 18, 1942, Serial No. 108,273

Term of patent 14 years

To all whom it may concern:

Be it known that I, John E. Hard, a citizen of the United States, residing at Cranston, in the county of Providence and State of Rhode Island, have invented a new, original, and ornamental Design for a Waterproof Jacket, of which the following is a specification, reference being had to the accompanying drawing, forming part thereof.

of a waterproof jacket showing my new design, and

Figure 2 is a similar view of the waterproof jacket shown in Figure 1 with the collar open.

The back of the jacket is conventionally plain.

I claim:

The ornamental design for a waterproof jacket, substantially as shown and described.

JOHN E. HARD.
